UNITED STATES PATENT OFFICE.

EDWARD E. GOLD, OF NEW YORK, N. Y.

STEAM-HEATING SYSTEM FOR RAILWAY-CARS.

No. 850,923.

Specification of Letters Patent.

Patented April 23, 1907.

Application filed June 20, 1904. Serial No. 213,428.

To all whom it may concern:

Be it known that I, EDWARD E. GOLD, a citizen of the United States, residing in the borough of Manhattan, city, county, and State of New York, have invented certain new and useful Improvements in Steam-Heating Systems for Railway-Cars, of which the following is a specification.

This invention relates to the regulating or controlling of steam admitted from the usual main or train pipe to the radiating-pipes carried in the car.

By means of this invention the quantity of steam admitted to a car is automatically controlled preferably by the live steam in or adjacent to the train-pipe, or at least before it is passed through the radiators, and thus the overheating of the cars is avoided and the unequal distribution of steam gradually diminishing from the front to the rear car of a long train, which has been a very serious matter in previous systems, is avoided or considerably mitigated.

According to this invention a valve controlling the supply of steam to the system of piping within the car is controlled by a thermostat, which is exposed preferably to the live steam immediately after the steam passes through the valve. The expansive element of the thermostat is preferably exposed on the one side to the atmosphere within the car and on the other side to the steam. Preferably, also, the valve is under hand control, so that it may be opened or closed by hand and so that also the pressure of steam admitted to the car may be regulated and the pressure in the train-pipe maintained to the very end of even a long train.

Various other improvements are referred to in detail hereinafter.

The accompanying drawings illustrate certain embodiments of the invention.

Figure 1 is a diagrammatic view of the piping for a single car. Fig. 2 is a sectional view of the piping through which the steam passes from the train-pipe to the car. Fig. 3 is a similar view of a slightly different form of the invention.

Referring to the embodiment illustrated, the usual train-pipe A extends under the entire length of each car, the several sections being united by sections of flexible pipe in the usual manner and the front end being connected with the locomotive-boiler by means of the usual pressure-reducing valve.

A system of piping B within the car typifies any suitable heating system either by direct or indirect radiation or otherwise. Steam is admitted from the train-pipe A by a branch C to the pipes within the car and after circulating therethrough is drained off by a trap D beneath the car, the steam passing to the trap through a pipe E and sediment-well F. The usual train-pipe valve G may be employed to close the train-pipe at one side or the other of the pipe C when the car is at the rear of a train, or valves may be employed one at each end of the car for the same purpose, as is well understood by those skilled in the art.

The passage of steam through the pipe C into the radiating-pipes B is subject to control by hand or by a thermostatic device at will. The hand-valve and thermostatic device may be combined in one structure, as in Fig. 3, or, as in the preferred form of Figs. 1 and 2, a simple hand-valve H may be provided separately from the thermostatic device J. The hand-valve H is preferably in advance of the thermostatic valve to permit cutting off the steam therefrom. It may be, for example, an angle-valve connecting the vertical section of pipe C with a horizontal section C', the thermostatic device J being interposed between the sections C' and C' of the horizontal pipe and provided also with a vertical stem. The hand-valve H will ordinarily be wide open when the car is being heated. The valve K will then be opened or closed automatically to admit steam as desired.

Any suitable thermostatic device in which the expansive member is exposed to the live steam may be used. In the construction illustrated a valve K has its stem L extended upward to connect with a diaphragm M, forming with the casing N a chamber open only to the steam-piping on the exit side of the valve. The valve is arranged to open in the direction of the steam-pressure, which arrangement permits of the simplest construction with the thermostat above the pipe and having direct connection with the valve-spindle and with the exit side of the valve. Upon the upper side of the diaphragm M is the expansive member O, consisting of a thin sheet-metal vessel attached to the diaphragm M and containing liquid of any desired boiling-point. An upper casing P is connected to the lower casing N of the thermostat by means of flanges Q, bolted together and em-

- bracing between them the edge of the diaphragm M. The expansive member O and stem L are pressed down, preferably through an interposed strong spring R, by means of an 5 adjusting-screw S, screwing through the upper casing P and provided with an upper square end or a handle or other suitable means for turning it. A set-nut T fixes the shaft S in the desired position of adjustment.
- 10 The casing P on the upper side of the diaphragm is apertured, as at U, so as to expose the upper part of the expansive device to the temperature of the surrounding atmosphere, preferably the temperature within the car, 15 while the under side thereof is exposed to the steam within the lower casing N. A light spring V is preferably provided in the casing N, tending to open the valve K.
- 10 The compression of the spring R having 20 been regulated to a desired extent by the screw-shaft S, steam in the pipe C', being of a higher pressure, opens the valve K and passes into the radiating-pipes within the car. In very cold weather the steam in the radiating- 25 pipes condenses and runs off rapidly, so that the temperature applied to the under side of the expansive member O is not very great, the coolness of the atmosphere in the car acting in the same way to retain the liquid in the 30 expansive member below its boiling-point.
- As soon as the atmosphere within the car becomes heated, however, the current of steam through the pipes is slower and the steam-pressure therein greater, and the heat applied 35 not only to the under side but to the upper side of the expansive member gradually increases until the liquid therein is vaporized and the member extended sufficiently to shut the valve K. The valve remains shut until 40 the falling pressure in the radiating-pipes and in the expansive member O permits the pressure in the pipe C', assisted by the spring V, to open the valve again. By suitably adjusting the pressure of the closing-spring R 45 the temperature of the car may be very accurately controlled. Furthermore, the expansive member O in conjunction with the spring R will act to close the valve before the pressure in the radiating system reaches that 50 in the train-pipe. The difference in pressure between the train-pipe and the radiating-pipe in the car will be equal approximately to the pressure exerted by the closing-spring R and as soon as expansion takes place by 55 the expansive member O, the spring V, being of practically inconsiderable strength as compared with the spring R. The pressure in the train-pipe is always greatest in the front cars and diminishes gradually, depending 60 upon the length of the train, the weather, and other matters. In long trains in severe weather the pressure is apt to fall so rapidly in the train-pipe that the rear cars cannot get sufficient steam to keep them heated. By 65 suitably adjusting the pressure of the springs

R in the several cars of a train, making this pressure gradually less from the front to the rear, the pressure of steam in the train-pipe is conserved so that at the rear end there is sufficient pressure for warming the cars.

70

The functions of a hand-valve and an automatic valve may be combined in one, as indicated at J', Fig. 3. Here it is the stem of the angle-valve H' which is extended upward and connected with the expansive member O, 75 as in Fig. 2. The screw-shaft S in this case is provided with a hand-wheel W and the set-nut for the shaft is preferably omitted. It will be clear that by compressing the spring R until its convolutions close against each 80 other any further movement of the shaft S will close the valve positively. Upon sufficiently unscrewing the shaft S the valve will be automatically lifted either by the pressure of steam in the pipe C or, if that be lacking, 85 by the light spring V. Screens X may be provided for preventing dirt or other obstructions from entering the valves.

80

Though I have described with great particularity of detail certain specific embodiments of the invention, yet it is not to be understood therefrom that the invention is limited to the specific embodiments disclosed. Various modifications thereof in detail and in the arrangement and combination of the 90 parts may be made by those skilled in the art without departure from the invention.

90

What I claim is—

1. A steam-heating system for a railway-car comprising a train-pipe, a heater within the car, a valve controlling the supply of steam to said heater and a thermostat controlling said valve and exposed to the live steam immediately beyond the valve, and exposed also to the atmosphere.

100

2. In a steam-heating system for a railway-car, a thermostatically-controlled admission-valve comprising a valve proper opening with the pressure, and an expansive device exposed to the live steam immediately at the discharge side of the valve and exposed also to the atmosphere, said expansive device arranged to close said valve by its expansion.

110

3. In a steam-heating system for a railway-car, a thermostatically-controlled admission-valve comprising a valve proper opening with the pressure, an expansive device exposed to the live steam immediately at the discharge side of the valve and exposed also to the atmosphere, said expansive device arranged to close said valve by its expansion, and a spring tending to open said valve.

115

4. In a steam-heating system for a railway-car, a thermostatically-controlled admission-valve comprising a valve proper, a diaphragm M, and an expansive device O carried upon and attached to the outer side of said diaphragm and exposed on its outer side 120

125

130

to the atmosphere, the inner side of said diaphragm being exposed to the steam.

5. In a steam-heating system for a railway-car, a train-pipe, a heater within the car, a thermostatically-controlled admission-valve comprising a valve proper between said train-pipe and said heater, and an expansive device arranged to close said valve by its expansion and exposed to the heat of the live steam immediately upon the discharge side of the valve, a spring bearing upon said expansive device and through it upon said valve in a direction to close the same, and an adjustable device bearing upon said spring to compress the same and adapted to compress the spring to its limit and to move further to positively close the valve.

6. In a steam-heating system for a railway-car, a train-pipe A, a heater B within the car, a thermostatically-controlled admission-valve J between said train-pipe and said heater and comprising a valve proper K opening in the direction of the pressure, and a thermostat connected to the stem of said valve to close the same by its expansion and exposed to the heat of the live steam immediately upon the discharge side of said valve, a spring R bearing upon said thermostat and through it upon said valve in a direction to

close the same, and an adjusting-screw S 30 bearing upon said spring to compress the same and adapt it to press the spring to its limit and to move further to positively close the valve.

7. A steam-heating system for a railway-car including a train-pipe A, radiating-pipes B within the car, a trap at the exhaust end of said pipes normally closing them so as to maintain pressure therein, a valve proper K arranged in a branch between said train-pipe 35 and said radiating-pipes, a flexible diaphragm M connected to said valve proper and exposed on one face to the steam-pressure beyond the valve and in a direction to open the valve, and on the other face to the pressure of the atmosphere, and a heat-expansible member O exposed on one side to the heat of the steam and on the other side to the atmosphere, and adapted when expanded to exert a pressure upon said diaphragm in a direction 40 45 to close the valve.

In witness whereof I have hereunto signed my name in the presence of two subscribing witnesses.

EDWARD E. GOLD.
